COIL CLEANING METHOD

George M. Gump, Cincinnati, Ohio

Application November 5, 1938, Serial No. 239,090

2 Claims. (CL 225—12)

This invention relates to the cleaning of coils and pipes and more in particular to an improved method for cleaning beer coils.

An object of the invention is to provide a compact, portable coil cleaning apparatus having a minimum of moving parts.

A further object of the invention is to disclose a new and improved method of thoroughly and quickly rinsing out the interior of coils and pipes.

Still a further object of the invention is to provide a compressor unit which will continuously provide quantities of rinse solution having admixed therewith quantities of gas for producing a frothy rinse solution.

These and other objects are attained by the means disclosed herein and shown in the accompanying drawing, in which:

Fig. 1 is a diagrammatic view of a typical coil cleaning set up embodying a compressor made in accordance with this invention.

Fig. 2 is a vertical cross-sectional view taken through the compressor unit shown in Fig. 1.

It has long been customary to clean beer coils either by passing live steam through said coils or by forcing a suitable chemical solution through said coils, however, cleaning with steam has the great disadvantage of being dangerous to persons because of its inherent qualities. Steam is also undesirable because of the latent heat transferred from the steam to the coils and pipes during the cleaning operation which results in overtaxing of the cooling system when beer is reintroduced into the hot lines and coils.

The present invention is concerned with an improvement in the method of cleaning beer coils by the so-called chemical method in which the coils are cleaned by the action of suitable chemicals in solution which are circulated through said coils.

In a typical dispensing set up, as shown in Fig. 1, beer is drawn from a barrel or other suitable container 10 through valve 11, coupling 12, pipe 13, through floor 14, through cooling coil A and thence to a dispensing faucet 15. A suitable drain pan 16 may be disposed below the faucet to catch faucet drippings which in turn are collected and conducted to a sewer by means of a suitable pipe as 17.

In a like manner the contents of container 18 may be drawn through valve 19, coupling 20, pipe 21, to cooling coil B, thence out through dispensing faucet 22.

It should be understood that it is customary to provide suitable refrigeration means, not shown, around cooling coils A and B for chilling

the contents of said coils prior to being discharged through faucets 15 and 22. This system, except for slight modifications comprises a standard beer dispensing installation.

Due to the inherent chemical qualities of beer it is mandatory, for sanitary reasons, to periodically cleanse the coils and pipes through which the beer is drawn. When the chemical method is employed to cleanse the coils and pipes it becomes necessary to provide a pump to properly circulate the chemical cleaning solution through the pipes comprising the system.

The pump unit of the present invention comprises a diaphragm type compressor 23 driven by a suitable electric motor 24 by means of belting 15. As clearly shown in Fig. 2 compressor 23 comprises an upper section 27 and a lower section 26 secured together by any suitable means such as bolts 28. The lower section 26 houses an eccentric 29, which when driven by suitable means, not shown, imparts a reciprocating motion through strap 130 to connecting rod 30. The free end of connecting rod 30 terminates in an annular plate 33, which is secured to a flexible diaphragm 31 by means of screw 32 which tightly secures plates 33 and 34 to opposite sides of said diaphragm as shown. Diaphragm 31 may be of leather or any other suitable flexible substance. The outer periphery of diaphragm 31 is secured between annular seat 35 and flange 36 of compression dome 37. Dome 37 is provided with a standard flap intake valve 38 and discharge valve 39 as shown. An intake pipe 40 extends through chamber 41 terminating in a gas tight and fluid tight fit around intake valve 38, whereby said intake valve is shielded from the contents of pressure chamber 41. A suitable discharge pipe 42 is provided through a housing 43 which defines the upper portion of pressure chamber 41. It should here be noted that the end of discharge pipe 42 extends into chamber 41 up to within a short distance of dome 37 for a reason to be hereinafter more fully disclosed.

A safety valve comprising a ball 44 of suitable material is ever urged against its annular seat 45 by the action of a spring 46 which is maintained in place by an apertured plug 47. A pipe 48 connects the interior of plug 47 to intake pipe 40, as clearly shown. This safety valve permits the medium housed within chamber 41 to by-pass 50 back to the intake line whenever the pressure within chamber 41 exceeds the counter pressure of spring 46, whereby damage to the compressor or to pipe lines being cleaned, is prevented.

A suitable annular gasket 49 may be interposed 55

between flange 36 of dome 37 and flange 50 of housing 43 to prevent any leakage from chamber 41.

5 Discharge pipe 42 comprises a T fitting, having a valve 51 interposed in leg 52 as shown.

A diaphragm compressor as described is utilized for cleaning coils A and B and piping 13 and 21 in the following manner, reference being had to Fig. 1.

10 The following hose connections are made prior to the start of the cleaning operation: A hose 53 is connected to intake pipe 40; one end of a hose 54 is connected to discharge pipe 42 the other end terminating in a faucet cup 55 which is 15 adapted to fit over the end of a faucet 15 as shown (see broken line 100); a third hose 56 connects leg 52 of the T discharge pipe 42 to a suitable water supply tap 57. The free end of intake hose 53 is positioned as shown by broken lines 58 so 20 that the compressor will pump air. After these preliminary connections have been made the valve 51 is closed and the motor 24 is started whereby compressed air is delivered via hose 54 to faucet 15. Faucet 15 is then opened with the 25 result that any fluid in coil A and line 13 is forced back into container 10 by the compressed air. When the fluid in line 13 has all been thusly pumped into container 10, faucet 15 is closed. Faucet cup 55 is then placed upon faucet 22 and 30 the process is repeated, whereby the contents of coil B and line 21 are pumped back into container 18. If desired, the pump may now be stopped.

35 Valves 11 and 19 are then closed and pipes 13 and 21 disconnected therefrom at couplings 12 and 20 respectively after which the ends of said pipes are connected together to form a complete circuit with faucet 15 at one end and faucet 22 at the other end. Faucet 15 is opened, then 40 faucet 22 is opened followed by the opening of valves 51 and 57 in order. This permits the hydrant water to course through faucet 22, coil B, pipe 21, pipe 13 through coil A and out through faucet 15 whereby the beer foam and other undesirable substances in said coils and pipes is rinsed out. This flushing action is continued until only clear water is discharged through faucet 15, at 45 which time valves 57 and 51 are closed.

50 Motor 24 is then started and only air is pumped, whereby the water in chamber 41 and in coils A and B and lines 21 and 13 is blown out through faucet 15. By reason of the fact that the end of discharge pipe 42 terminates close to the bottom of chamber 41, practically all of the liquid 55 in said chamber is exhausted before any air can be discharged, and likewise this construction traps a certain amount of air in the top of said chamber when a liquid is being pumped.

60 After all the water thusly has been discharged from the pipe lines as will be evidenced when air is discharged from open faucet 15, the end of intake hose 53 is placed into a bucket 60 containing a suitable chemical cleansing and sterilizing solution—see broken lines 59. This process is 65 continued until the chemical solution is discharged through faucet 15 at which time the free end of the intake hose 53 is secured to faucet 15 whereby the chemical solution is caused to circulate through the coils and associated pipes for a suitable period of time, after which the end of inlet hose 53 is removed from faucet 15 and positioned as at 58 where air is pumped through the system until all of the chemical solution has been exhausted from the lines. Said chemical

solution may be discharged from faucet 15 into drain 16.

After the chemical solution has been expelled and while the compressor is delivering air to the system via discharge pipe 54, valves 51 and 57 are 5 opened with the result that a frothy air laden solution of water is flushed through the coils and associated pipes and exhausted through faucet 15. By reason of the operating characteristics of a diaphragm pump and the relative location 10 of the end of discharge pipe 42 to the bottom of chamber 41, this pump will continuously deliver a frothy solution of air and water as long as desired. It is this ability to continuously deliver a frothy solution of air and water under 15 pressure that results in the pump becoming an invaluable asset to those industries in which coils and pipes are to be cleaned.

After this flushing operation has been completed the valves 51 and 57 are closed whereupon 20 only air is pumped through the system, which blows all of the water out of the coils and pipes. The pump is then stopped, faucets 15 and 22 closed, the pipes 13 and 21 are disconnected and reconnected to couplings 12 and 20 respectively, 25 valves 11 and 19 opened, discharge hoses 54 and 56 disconnected from faucet 22 and tap 57 respectively and the system is once again ready for dispensation of the contents of containers 30 10 and 18.

It is to be understood that diaphragm compressor 23 and motor 24 may be mounted upon a suitable portable standard as 61 whereby said unit is rendered portable.

It should here be noted that it is characteristic of a diaphragm type compressor to build up a substantially constant pressure in pressure chamber 41, but said pressure is characterized by rapid pulsations set up by the operation of diaphragm 31. These rapid pulsations in conjunction with the comparatively constant pressure within chamber 41 causes any suitable gaseous substance, such as air, to be forced into the fluid stream supplied through T pipe 52 as tiny globules or bubbles whereby a frothy solution results 45 comprising an admixture of gas particles and fluid. Such a gas should be substantially non soluble in the fluid used in order that the frothy condition will continue as long as the solution is confined within the coils or conduits. Likewise 50 it is desirable that the gas used be substantially inert under the conditions encountered during the cleaning process in order that no harmful results will follow such operation.

The process as described greatly speeds up the 55 usual process of rinsing without sacrificing thoroughness since the minute gas particles tend to scour the tube walls whereby the particles loosened by the chemical solution are dislodged and are carried in suspension through said lines by the 60 fluid whereupon a better job of rinsing is accomplished than is possible with either water or the gas alone.

It should be understood that an admixture of air and water has been referred to in the specification merely for the purpose of illustration and I do not wish to limit myself to these two substances since numerous other liquids and gases may be substituted within the scope of the appended claims without departing from the spirit 70 of the invention.

What is claimed is:

1. The method of flushing and cleaning beer dispensing coil systems and their faucets, which method comprises the steps of connecting one end 75

5 of the coil system to a fresh water supply and pumping water therefrom through the system to initially flush it, then draining the system of the flush water, then connecting the ends of the coil system to furnish a closed circuit, and injecting and circulating a chemical cleaner within the system, then draining the system of the chemical cleaner, and thereafter filling the system with rinse water and circulating said rinse water through the system with the aid of air under pressure delivered thereto in sharp and sudden high-speed pulsations for breaking up the column of water in the system at infinitesimally small intervals, thereby to impart a scouring effect to the frothy admixture of water and air in the system, and thereafter draining the system.

10 2. The method of flushing and cleaning beer dispensing coil systems and their faucets, which

method comprises the steps of connecting one end of the coil system to a fresh water supply and pumping water therefrom through the system to initially flush it, then draining the system of the flush water, then connecting the ends of the coil system to furnish a closed circuit, and injecting and circulating a liquid chemical cleaner within the system with the aid of air under pressure delivered thereto in sharp and sudden high-speed pulsations for breaking up the column of liquid in the system at infinitesimally small intervals, thereby to impart a scouring effect to the frothy admixture of liquid and air in the system, then draining the system of the chemical cleaner, then filling the system with 15 rinse water and circulating said rinse water through the system, and thereafter draining the system.
